United States Patent Office

Des. 211,750
Patented July 23, 1968

211,750

NECKTIE PRESSER

Harold Richards, 18 Lake Shore Drive, Eastchester, N.Y.
10709, and Jean Jacques Schnoll, 562 West End Ave.,
New York, N.Y. 10024

Filed Sept. 18, 1967, Ser. No. 8,623

Term of patent 14 years

(Cl. D49—1)

FIG. 1

FIG. 2

FIG. 3

FIG. 4

FIG. 5

FIG. 6

FIG. 1 is a top plan view of the necktie presser embodying our new design;

FIG. 2 is a bottom plan view thereof;

FIG. 3 is a side elevational view thereof;

FIG. 4 is a side elevational view thereof, of the opposite side from that shown in FIG. 3;

FIG. 5 is a rear end elevational view thereof; and

FIG. 6 is a front end elevational view thereof.

The dominant features of our design reside in the portions shown in full lines, the electric cord being shown broken away for convenience of illustration.

We claim:

The ornamental design for a necktie presser, as shown and described.
